UNITED STATES PATENT OFFICE.

JOHN C. DEHLS, OF BROOKLYN, NEW YORK, ASSIGNOR TO NATIONAL PNEUMATIC ACTION CO., INC., OF NEW YORK, N. Y., A CORPORATION OF NEW YORK.

AUTOMATIC MUSICAL INSTRUMENT.

1,096,157.

Specification of Letters Patent.

Patented May 12, 1914.

Application filed June 23, 1913. Serial No. 775,238.

To all whom it may concern:

Be it known that I, JOHN C. DEHLS, a citizen of the United States, and a resident of Brooklyn, in the county of Kings and 5 State of New York, have invented certain new and useful Improvements in Automatic Musical Instruments, of which the following is a specification.

The invention pertains more particularly 10 to what are commonly known as tracking devices or means for securing the proper alinement of the perforations in a music sheet with the openings in a tracker bar, and said invention consists in the novel features, arrangements and combinations of 15 parts hereinafter described, and particularly pointed out in the claims.

The difficulties incident to keeping a traveling perforated sheet with its perforations 20 in proper alinement with the openings in a tracker bar are well understood, and the object of my invention is to provide simplified and highly efficient means for maintaining such alinement, the features of my 25 invention automatically acting to restore the alinement of the perforations in the traveling sheet with the openings in the tracker bar at any time there should be a variance in such alinement.

30 In carrying out my invention I may employ either a rigidly held tracker bar or a slideable tracker bar located between a music spool which is free to have limited endwise movement and a wind-up spool which is not 35 capable of endwise movement, and with said features I combine a pneumatic or bellows which is normally under constant light suction and comprises two chambers substantially subdivided by a central partition, and 40 a hinged frame capable of being moved against the perforated sheet in close proximity to the tracker bar and which frame is hollow in its end portions and has small openings facing the perforated sheet closely 45 adjacent to the edges thereof, the hollow end portions of said frame being respectively connected with the aforesaid pneumatic so that upon any lateral movement of the perforated sheet sufficient to expose 50 either of the openings in said frame, atmospheric air may enter such opening and pass to the pneumatic, with the result that the subdividing partition therein will move in one direction or the other and effect the end- 55 wise movement of the music spool for the

purpose of correcting the travel of the music sheet. I also preferably connect the tracker bar by a link with the partition of the pneumatic in order that said bar, then slideable, may coöperate with the aforesaid hinged frame in securing the proper register of the perforations in the music sheet with the openings in said bar.

The invention will be fully understood 60 from the detailed description hereinafter presented, reference being had to the accompanying drawings, in which:

Figure 1 is a side elevation, partly broken away and partly in section, of the music-box of a piano player equipped with the 70 features constituting my invention, the music sheet being shown as traveling from the music spool to the take-up spool; Fig. 2 is a vertical section through the same on the dotted line 2—2 of Fig. 1; Fig. 3 is an end 75 view of the same taken from the right hand end of Fig. 1; Fig. 4 is a detached rear view, partly broken away and partly in section, of the hinged frame which during the employment of the invention engages the 80 traveling sheet adjacent to the tracker bar, Fig. 2 being presented to show the openings in the rear side of the end portions of said frame and also the means by which communication between the end portions of said 85 frame is prevented; Fig. 5 is an enlarged detached sectional view through the central portion of one of the horizontal members of the hinged frame and is presented to illustrate the means for adjusting the length of 90 the same to the requirements of the width of the music sheet; Fig. 6 is a longitudinal section through a portion of one of the members of the hinged frame and illustrates the 95 employment of a valve to be operated by the edge of the music sheet as a substitute for the opening, shown in Fig. 4, in the rear side of the hinged frame for engaging the face of the traveling sheet, the section on which Fig. 6 is taken being indicated by the 100 dotted line 6—6 of Fig. 7, and Fig. 7 is a front elevation of the features shown in Fig. 6 and illustrates a portion of the traveling music sheet in engagement with the valve arm for operating the valve on variations of travel in the sheet.

In the drawings, 10 designates a customary form and construction of music-box adapted to support a tracker bar 11, a music spool 12, and a take-up spool 13, to receive a 110

music sheet 14 as unwound from the spool 12 and to permit the re-winding of said sheet on said spool 12 when the latter is to be removed from the frame 10. The means for rotating the spools 12, 13 are well known in the art and have not, therefore, been illustrated, my invention not pertaining to the shifting gears or other like parts of a piano player. The spool 12 has a socket at one end 10 to receive a spring-pressed spindle 15 of known form and construction, and at its other end said spool is detachably keyed to the inner end of a spindle 16 which, in this instance, I carry through a bearing in the 15 vertical side of the box or frame 10 and mount thereon a grooved disk 17 to receive the lower rounded end of a lever 18 which is pivoted to the supporting bracket 19 and has its upper end connected with one end of 20 a rod 20, whose other end is connected with the partition 21 which subdivides the bellows or pneumatic into two compartments 22, 23, said compartments being, however, in communication with each other through a 25 small pin-hole 24 in the lower end of said partition. The pneumatic or bellows, numbered 25 as a whole, is in communication through a conduit 26 with means for creating a partial vacuum therein.

30 Between the sides of the music box 10 and journaled in said sides so as to be capable of a hinged movement, I mount a frame (numbered as a whole 27) composed of two side members 28, 29 and two horizontal members 35 30, 31, respectively, connected with said side members and carried thereby, said members 30, 31 being separated from each other a distance slightly greater than the width of the tracker bar 11 and adapted to engage the 40 traveling sheet 14 above and below said tracker bar so as to press said sheet lightly but firmly against the perforated face of said bar. The side members 28, 29 of the frame 27 are hollow and have right-angular 45 portions 32, 33, respectively, at their lower ends extending through the bearings in the sides of the music box 10 and respectively connected by conduits 34, 35 with the chambers 22, 23 of the pneumatic 25, said conduits being flexible so that the frame 27 may 50 be conveniently turned upwardly against the traveling sheet 14, as shown in Fig. 1, or downwardly therefrom, as may be desired. The frame 27 constitutes one of the more 55 important features of my invention, although the invention is not limited to the specific form of frame 27 shown. The horizontal members 30, 31 of the frame 27 are provided on their rear faces in close proxim- 60 ity to the edges of the traveling sheet 14 with small apertures or air inlet openings 36, 37, which, during the proper travel of the sheet 14, are closed by said sheet, but which on the departure of said sheet from its 65 proper alignment with the openings in the

tracker bar 11 will, at one side or other of the sheet, become exposed or uncovered, and permit atmospheric air to pass to the pneumatic 25 and operate, with the other features of the invention, to restore the traveling 70 sheet to its proper line of travel.

The frame 27 comprises two sections connected together by turn-buckles or nuts 38, by means of which said sections may be adjusted laterally from or toward each other 75 for the purpose of adjusting the same and the openings 36, 37 therein to the width of the traveling sheet 14. The two sections of the frame 27, while hollow, are separated from each other, so far as air communication is concerned, by means of internal plugs 80 39 (Fig. 4), as well as by the turn-buckles or nuts 38, it being the intention that each end portion or section of said frame shall act independently of the other in restoring 85 the sheet 14 to its proper line of travel. I provide the frame 27 with a spring 40 which may serve to lightly press the upper portion of said frame or the members 30, 31 thereof against the traveling sheet 14 above and 90 below the tracker bar 11, as shown in Fig. 2, said spring 40 also when the frame 27 is turned outwardly and downwardly from its operative position shown in Fig. 2, acting to hold said frame in its then lower position. 95 The frame 27 will be held in its upper position during the travel of the music sheet 14 and may be turned to its lower position when it is desired to rewind said sheet upon the spool 12 and place a further music sheet 100 within the box 10. The frame 27 may be moved to its operative and inoperative position by hand, but in the present instance I have provided a pneumatic 41 by means of which said frame 27 may be moved automatically, said pneumatic 41 at its hinged side having an arm 42 pivotally connected with a rack bar 43 in mesh with a gear wheel 44 secured on the horizontal member 33 of said frame 27.

In Fig. 3 I illustrate the rack bar 43 and gear wheel 44 as having been operated rearwardly by vacuum in the pneumatic 41 to turn the frame 27 to its operative position, and by the arrow shown in Fig. 3 I 115 indicate the movement that the gear wheel 44 will have when atmospheric air is admitted to the pneumatic 41 and the latter opens to move the rack bar 43 forwardly for the purpose of turning the frame 27 forwardly and downwardly from the traveling sheet 14. I may employ the pneumatic 41, arm 42, rack bar 43, and gear wheel 44 for effecting the automatic movement of the frame 27, and in such employment the spring 40 is also an advantage in that it assures a uniform engagement of the teeth of the gear wheel 44 with the teeth of the rack bar 43 and an even uniform 120 movement of the frame 27 without undue 125 movement of the frame 27 without undue 130

freedom of the moving parts which might cause a rattling noise or be otherwise objectionable. While I prefer to employ automatic means for moving the frame 27 from one to the other of its two positions, it is perfectly obvious that said frame may be operated by hand and that under such condition the spring 40 is useful in binding the frame 27 in each of said positions. Stops 10 45, 46 may be employed, if desired, for preventing undue movement of the frame 27 from one to the other of its positions, as shown in Fig. 2.

The hinged or movable side of the pneumatic 41 is connected with a spring 60 whose normal tendency is to move said side to its open position and cause the rack-bar 43 to turn the frame 27 to its lower or inoperative position. A tube 61 communicates 20 with the interior of the pneumatic 41.

In the operation of a musical instrument employing my invention, vacuum is created in the player action to permit the player to work, as in playing, as usual; and this 25 vacuum acts through the tube 61 to close or collapse the pneumatic 41 in opposition to the force of the spring 60 and effect, through the rack-bar 43, the movement of the frame 27 to its operative position. On re-rolling 30 the music sheet on the instrument, vacuum communication is cut off from the action, as customary in all usual players, and this will have the effect of cutting off the vacuum from the pneumatic 41 and permitting the 35 spring 60 to, through the hinged side of the pneumatic 41, arm 42 carried thereby, rack-bar 43 and gear wheel 44, move the frame 27 to its lower or inoperative position.

I illustrate the traveling sheet 14 and 40 frame 27 in their normal operative position in Figs. 1 and 2, and it will be observed that the openings 36, 37, indicated by dotted lines in Fig. 1, are closely adjacent to the extreme vertical edges of the sheet 14. So 45 long as the traveling sheet 14 remains in proper alignment with the usual apertures in the tracker bar 11, the pneumatic 25 and frame 27 will be practically inoperative, except for the fact that the frame 27 performs 50 the duty of keeping the traveling sheet 14 in suitably close relation to the front face of said tracker bar. On any variation, however, of the travel of the sheet 14 toward the right, looking at Fig. 1, the openings 55 36 in the members 30, 31 of the frame 27 will become partly or wholly exposed by being uncovered by the divergence of the traveling sheet, and atmospheric air will then enter said openings and passing through

60 the side member 28 of the frame 27 and conduit 34 will enter the chamber 22 of the pneumatic 25, with the result that the disturbance in said chamber of the partial vacuum will effect the movement of the partition 21 toward the right and acting

through the rod 20, lever 18, wheel 17 and spindle 16, move the music spool 12 toward the left, for the purpose of correcting the travel of the music sheet and restoring it to its proper alignment with the openings in the tracker bar 11. The movement toward the right of the partition 21 also, in the preferred construction, results in the tracker bar being moved slightly toward the right so that its perforations may, to the maximum extent, be kept in alignment with the openings in the perforated sheet 14 during the lateral movement of said sheet. On any divergence of the line of travel of the sheet 14 toward the left, looking at Fig. 1, the openings 37 in the members 30, 31 of the frame 37, will become more or less exposed with the result that atmospheric air passing through the same will enter the side member 29 of said frame and thence travel 70 through the member 33 and conduit 35 and enter the chamber 23 of the pneumatic 25, with the result that the partition 21 of said pneumatic will move toward the left and, drawing through the rod 20 and lever 18, 75 move the grooved wheel 17 and spindle 16 toward the right and allow the spring-pressed spindle 15 to move the music spool 12 correspondingly toward the right, following up the spindle 16, for the purpose of 80 correcting the travel of the music sheet 14 and restoring it to proper alignment with the perforations or openings in the tracker bar 11, the said tracker bar by its connection with the partition 21 being given a 85 movement intended to keep its openings or perforations as far as may be possible in alignment with the perforations in said 90 music sheet.

As the music sheet 14 moves to the left to recover the openings 36 in the frame 27 or toward the right to recover the openings 37 in said frame, while regaining its proper line of travel, said openings becoming excluded from the entrance of atmospheric air, 100 allow the pneumatic 25 under the suction through the conduit 26 to regain its normal condition shown in Fig. 1 ready to act on any further divergence of the line of travel of the music sheet.

I illustrate the frame 27 as having two horizontal members 30, 31 to press against the traveling sheet 14 and as each having at each end air inlet openings 36, 37 to be uncovered by the sheet 14 as it diverges laterally toward the right or left, but it is to be understood that the invention would be entirely operative if the openings in the member 30 were absent and the openings in the member 31 present or the openings in the member 30 present and the openings in the member 31 absent, since the atmospheric air passing into the openings of either the member 30 or the member 31, would result in the pneumatic 25 acting to shift the music spool 115 120 125 130 135 140

12 and restore the sheet 14 to its proper line of travel. The mechanism is more sensitive in its action when both the members 30, 31 are employed with each having perforations 5 or openings 36, 37 therein. I also prefer to employ both the members 30, 31 because when both members are employed I may press the traveling sheet 14 above and below the tracker bar against said bar, but one of 10 said members may be entirely omitted since either of said members may have the openings 36, 37 and also serve to press the traveling sheet against the tracker bar. In some instances it may not be possible to employ 15 both of the members 30, 31, for want of space or other reason, and in such instance I will prefer to omit the upper member 30 and employ only the lower member 31, the frame 27 with only said lower member 31 occupying 20 less space than would be required by said frame having both members 30, 31. I deem it of very great advantage to have an exterior frame 27 of any suitable construction having openings 36, 37 near its end portions 25 normally closed by the traveling sheet 14 and adapted to be opened on the divergence of the line of travel of said sheet for the purpose of operating the pneumatic to correct said line of travel and maintain the 30 perforations in the music sheet in line with the openings in the tracker bar, and hence I do not limit my invention to the special form of the frame 27, although I have shown in the drawings the form of frame preferred 35 by me. It is not necessary, also, that the tracker bar 11 be slidable and connected with the partition 21, but obviously the rendition of the music will be more accurate when said bar is slidable and connected with said partition so that the openings in the bar may 40 follow the perforations in the music sheet 14.

The frame 27 is slidably mounted in its bearing in the sides of the music box 10 so that when desired it may be shifted laterally 45 for the purpose of transposing, and, as shown in Fig. 1, I connect said frame 27 with an auxiliary frame 47 extending through the sides of the music box and through bearings 48 and provide said frame 50 47 with an internally threaded adjusting nut 49 engaging a thread on said frame and confined at one edge in a recess 50 in the bottom of the music box. When the nut 49 is turned in one direction or the other it will 55 be confined in the recess 50 and engaging the thread 51 on the frame 47 cause said frame to travel laterally and move in a corresponding direction the frame 27. The frame 47 is detachably connected with the 60 frame 27 by means of screws 52, and preferably the frame 47 is provided with a pointer 53 in operative relation to a scale 54 on the box 10 to guide the operator in adjusting said frame.

65 In Figs. 1, 2 and 4 I illustrate the open-

ings 36, 37 in the members of the frame 27 as facing the traveling sheet 14 and to be covered or uncovered by the face contact of said sheet with said members. I may however provide valved openings beyond the 70 edges of the sheet 14 and depend upon the extreme vertical edges of the sheet to operate the valves for said openings, as I illustrate in Figs. 6 and 7, in which 55 represents one of the horizontal members of the frame 27 having an opening 56 outwardly beyond the traveling sheet 14 and provided with a valve 57 carried by a pivoted arm 58 normally adjacent to the edge of the sheet 14. The valve 57 is normally held in its closed position by means of a spring 59 and said valve will be opened in opposition to the force of said spring on any divergence of the traveling sheet 14 carrying its edge against the lever 58 tending to turn said lever outwardly 80 on its pivotal bearing. The uncovering of the opening 56 by the valve 57 results in the air entering the member 55 and flowing to the pneumatic 25, with the same result that is effected when the air enters the openings 90 36, 37 in the frame 27, as hereinbefore explained. Figs. 6 and 7 represent a modification of the invention in respect to the openings in the members 30, 31 for the admission of atmospheric air to or its exclusion from 95 the conduits 34, 35 leading to the pneumatic 25.

What I claim as my invention and desire to secure by Letters Patent, is:

1. In mechanism of the class described, 100 having a perforated music-sheet, in combination with an endwise movable spool for said sheet, means for moving said spool in one direction, and a tracker-bar, of means for moving said spool in the reverse direction comprising a frame movable toward and from said sheet and having a normally closed air passage to be opened by said sheet on a divergence from its line of travel, a pneumatic in communication with said 110 frame, and a connection from said pneumatic to said spool to shift the spool from said pneumatic.

2. In mechanism of the class described, 115 having a perforated music-sheet, in combination with an endwise movable spool for said sheet, means for moving said spool in one direction, and a tracker-bar, of means for moving said spool in the reverse direction comprising a frame movable toward and from said sheet and having independent normally closed air passages adjacent to its ends to be opened, one or the other, by the sheet on a divergence from its line of travel, a pneumatic having independent communication with the ends of said frame, and a connection from the pneumatic to said spool to shift the spool from said pneumatic.

3. In mechanism of the class described, 120 having a perforated music-sheet, in combi-

nation with an endwise movable spool for said sheet, means for moving said spool in one direction, and a tracker-bar, of means for moving said spool in the reverse direction comprising a frame movable toward and from said sheet and having a normally closed air passage to be opened by said sheet on a divergence from its line of travel, a pneumatic in communication with said frame, and a connection from said pneumatic to said spool to shift the spool from said pneumatic, said tracker-bar being longitudinally slid able and connected with the movable member of said pneumatic to be actuated therefrom.

4. In mechanism of the class described, having a perforated music-sheet, in combination with an endwise movable spool for said sheet, means for moving said spool in one direction, and a tracker-bar, of means for moving said spool in the reverse direction comprising a frame movable toward and from said sheet and having independent normally closed air-passages adjacent to its ends to be opened, one or the other, by the sheet on a divergence from its line of travel, a pneumatic having independent communication with the ends of said frame, and a connection from the pneumatic to said spool to shift the spool from said pneumatic, said tracker-bar being longitudinally slid able and connected with the movable member of said pneumatic to be actuated therefrom.

5. In mechanism of the class described, having a perforated music-sheet, in combination with an endwise movable spool for said sheet, means for moving said spool in one direction, and a tracker-bar, of means for moving said spool in the reverse direction comprising a frame movable toward and from said sheet and having independent normally closed air-passages adjacent to its ends to be opened, one or the other, by the sheet on a divergence from its line of travel, a pneumatic having independent communication with the ends of said frame, a connection from the pneumatic to said spool to shift the spool from said pneumatic, and means for shifting said frame relatively to the music-sheet for transposing.

6. In mechanism of the class described, having a perforated music-sheet, in combination with an endwise movable spool for said sheet, means for moving said spool in one direction, and a tracker-bar, of means for moving said spool in the reverse direction comprising a frame movable toward and from said sheet and having independent normally closed air passages adjacent to its ends to be opened, one or the other, by the sheet on a divergence from its line of travel, a pneumatic having independent communication with the ends of said frame, and a connection from the pneumatic to said spool to shift the spool from said pneumatic, said

frame having means for adjusting its length to meet the requirements of the music-sheet.

7. In mechanism of the class described, having a perforated music-sheet, in combination with an endwise movable spool for said sheet, means for moving said spool in one direction, and a tracker-bar, of means for moving said spool in the reverse direction comprising a frame movable toward and from said sheet and having independent normally closed air passages adjacent to its ends to be opened, one or the other, by the sheet on a divergence from its line of travel, a pneumatic having independent communication with the ends of said frame, a connection from said pneumatic to said spool to shift the same from the pneumatic, and a pneumatic for moving said frame to its operative and inoperative positions.

8. In mechanism of the class described, having a perforated music-sheet, in combination with an endwise movable spool for said sheet, means for moving said spool in one direction, and a tracker-bar, of means for moving said spool in the reverse direction comprising a frame extending across said sheet adjacent to and pressing the same against the tracker-bar and having independent normally closed air passages adjacent to its ends to be opened, one or the other, by the sheet on a divergence from its line of travel, a pneumatic having independent communication with the ends of said frame, and a connection from the pneumatic to said spool to shift the spool from said pneumatic.

9. In mechanism of the class described, having a perforated music-sheet, in combination with an endwise movable spool for said sheet, means for moving said spool in one direction, and a tracker-bar, of means for moving said spool in the reverse direction comprising a frame extending across said sheet adjacent to the upper and lower portions of and pressing the same against the tracker-bar and having independent normally closed air passages adjacent to its ends to be opened, one or the other, by the sheet on a divergence from its line of travel, a pneumatic having independent communication with the ends of said frame, and a connection from the pneumatic to said spool to shift the spool from said pneumatic.

10. In mechanism of the class described, having a perforated music-sheet, in combination with an endwise movable spool for said sheet, means for moving said spool in one direction, and a tracker-bar, of means for moving said spool in the reverse direction comprising a hinged frame having side members and a connecting member extending when the frame is in operative position across said sheet and said frame having independent normally closed air passages ad-

5 jacent to its ends to be opened, one or the other, by the sheet on a divergence from its line of travel, a pneumatic having independent communication with the ends of said frame, and a connection from the pneumatic to said spool to shift the spool from said pneumatic.

- 10 11. In mechanism of the class described, having a perforated music-sheet, in combination with an endwise movable spool for said sheet, means for moving said spool in one direction, and a tracker-bar, of means for moving said spool in the reverse direction comprising a hinged frame having side members and a connecting member extending when the frame is in operative position across said sheet adjacent to the lower edge of the tracker-bar and said frame having independent normally closed air passages adjacent to its ends to be opened, one or the other, by the sheet on a divergence from its line of travel, a pneumatic having independent communication with the ends of said frame, and a connection from the pneumatic to said spool to shift the spool from said pneumatic.
- 15 20 25 12. In mechanism of the class described,

30 having a perforated music-sheet, in combination with an endwise movable spool for said sheet, means for moving said spool in one direction, and a tracker-bar, of means for moving said spool in the reverse direction comprising a hinged frame having side members and two connecting transverse members extending respectively when the frame is in operative position across said sheet adjacent to the upper and lower edge portions of the tracker-bar and said frame having independent normally closed air passages adjacent to its ends to be opened, one or the other, by the sheet on a divergence from its line of travel, a pneumatic having independent communication with the ends of said frame, and a connection from the pneumatic to said spool to shift the spool from said pneumatic.

35 40 45 Signed at New York city, in the county of New York and State of New York, this 21st day of June, A. D. 1913.
